CLAIM

The ornamental design for a tape dispenser, as shown and
described.

DESCRIPTION

FIG. 1 is an isometric view of a tape dispenser according to
the present invention;

FIG. 2 is a front view of the tape dispenser illustrated in FIG.

1, the rear view being the mirror image thereof;

FIG. 3 is a top view of the tape dispenser illustrated in FIG.
1;

FIG. 4 is a bottom view of the tape dispenser illustrated in
FIG. 1;

FIG. 5 is a left side view of the tape dispenser illustrated in
FIG. 1; and,

FIG. 6 is a right side view of the tape dispenser illustrated in
FIG. 1.

The structure depicted by means of broken lines in the
figures has been shown for illustrative purposes only and
forms no part of the claimed design.
